UNITED STATES PATENT OFFICE.

EDWARD J. KELLY, OF MONONGAHELA CITY, PENNSYLVANIA.

CAR-WHEEL.

SPECIFICATION forming part of Letters Patent No. 288,817, dated November 20, 1883.

Application filed August 2, 1883. (No model.)

To all whom it may concern:

Be it known that I, EDWARD J. KELLY, of Monongahela City, in the county of Washington and State of Pennsylvania, have invented 5 certain new and useful Improvements in Cast Wheels; and I do hereby declare that the following is a full, clear, and exact description of the invention, which will enable others skilled in the art to which it appertains to make and 10 use the same, reference being had to the accompanying drawings, which form a part of this specification, in which—

Figure 1 is a longitudinal section, and Fig. 15 2 a transverse section on line $x-x$, of my invention as applied to a pit-car wheel.

My invention has relation to wheels of that 20 class which are loose upon and revolve upon their axle or shaft, and consequently require constant and ample lubrication.

25 My invention consists in a wheel wherein the hub is formed as an integral casting with the spokes thereof, in forming said hub with an interior chamber extending partially up into the spokes, and having communication 25 with the axle-opening by means of a diagonal slit in a sleeve which forms the bearing for said axle.

Referring to the accompanying drawings, A represents the rim of the wheel, B the spokes, 30 and C the hub. The hub C is cast in one piece with the spokes and rim, and is provided with the usual opening in its center for the reception of the axle, as shown, and designated by the letter a . Said hub is formed, 35 during the process of casting, with a central chamber, D, which surrounds the hub-opening a and receives the lubricating-fluid. The chamber D follows the contour of the hub, and extends some distance into the spokes B 40 B, forming recesses or pockets b therein. Openings or holes $c-c$ in the outside wall of chamber D serve for the admission of the lubricating-fluid to said chamber. These openings or holes are in a line drawn from the 45 center of the axle-opening through the spokes and the pockets b . Within the chamber D, on each side, and surrounding the axle-opening a , are two annular flanges, $e-e$, and upon the outside of said opening are flanges $e'-e'$. 50 These flanges are cast integral with the hub, and serve as a sleeve, in which the axle turns. The flanges $e-e$ form the inner wall of chamber D, and their inner edges are oppositely inclined, so as to form a diagonal slit, f , between them, through which the lubricant in

chamber C has access to the axle. My object in making the slit f diagonal is twofold. It prevents the formation of a ring or burr on the axle, which must inevitably occur if said slit were at right angles to the axle, and it 60 serves to distribute the lubricating-fluid over a greater surface than a slit cut or formed in the manner last mentioned.

It will be observed that the flanges $e-e$ taper toward their edges, the object of said taper 65 being to facilitate the removal of the sand core after casting, and to remove any particles of metal which may fall through the slit f when the central opening, a , is being cut out.

The operation of my invention is as follows: When it is desired to lubricate the axle, 70 the fluid proper to the purpose is poured into the chamber D through the opening c , which is uppermost, until it has filled the pocket b below. Upon the wheel beginning to revolve the 75 oil is carried around and a portion of it falls upon the axle through the slit f . The oil is distributed over a considerable portion of the axle by reason of the diagonal slit, and an even wearing of the surface of the same is 80 assured. When the wheel stops, the unused oil in chamber D gathers in the lowest pocket, b , to be again distributed, as before. Should any grit, sand, or other material gather in chamber D, the wheel may be removed from 85 its axle and the dirt shaken out through the slit f .

I am aware it is not broadly new to construct a car-wheel with an oil cavity or cavities around the hub, with an opening therefrom through the wall of the hub for admitting oil to the spindle or axle; but my invention embraces the novel idea of an inclined or oblique channel which has its inlets on different circumferential lines, and therefore of 95 such a form as to avoid sharp angles, which accumulate dirt, and to avoid the cutting of a channel or channels in the axle.

I claim—

The combination of wheel-rim A, spokes B, 100 and hub C, having chamber D, pockets b , openings $c-c$, flanges $e-e$, and inclined slit f , substantially as described, and for the purpose set forth.

In testimony that I claim the foregoing as 105 my own I have hereto affixed my signature in presence of two witnesses.

Witnesses: EDWARD J. KELLY.

S. P. KELLER,

W. W. MORRISON.
